UNITED STATES PATENT OFFICE.

CHARLES L. FAULK, OF CLEVELAND, OHIO.

CUFF-BUTTON.

1,391,620.

Specification of Letters Patent. Patented Sept. 20, 1921.

Application filed May 17, 1920. Serial No. 381,952.

To all whom it may concern:

Be it known that I, CHARLES L. FAULK, a citizen of the United States, residing at Cleveland, in the county of Cuyahoga and State of Ohio, have invented new and useful Improvements in Cuff-Buttons, of which the following is a specification.

An object of this invention is to produce a cuff button in which the sections constituting the same are hingedly connected and are provided with an interengaging shank and socket and means for locking the shank in the socket so that the hinged sections cannot be accidentally separated.

15 A further object is to produce a cuff button that may be highly ornamental and attractive in appearance, but which shall be of a simple construction and which shall be in the nature of a safety appliance, inasmuch as the elements constituting the same cannot become accidentally disconnected.

It is a still further object to produce a cuff button in which two elements in the nature of plates having incurved ends are hingedly connected together, one of such plates having on its inner face a shank, the other plate having a socket to receive the shank. In the socket is a spring which coengages with the shank to lock the same in the socket, while 30 means is provided for bringing the spring out of engagement with the shank to permit the swinging of the sections away from each other.

The foregoing, and other objects which 35 will appear as the nature of the invention is better understood, may be accomplished by a simple construction, combination and operative arrangement of parts, such as is disclosed by the drawings, in which,

40 Figure 1 is a perspective view showing the application of a cuff button constructed in accordance with this invention.

Fig. 2 is an edged view of the button, with the parts separated.

45 Fig. 3 is an approximately central longitudinal sectional view through the button with the parts connected.

Fig. 4 is a sectional view approximately on the line 4—4 of Fig. 3.

50 Fig. 5 is a sectional view approximately on the line 5—5 of Fig. 3.

Fig. 6 is a perspective view of a modification.

55 Fig. 7 is a sectional view taken approximately centrally through the shank and socket and illustrating in dotted lines the

manner in which the spring influenced jaws are brought out of engagement with the shank.

Fig. 8 is a detailed sectional view approximately on the line 8—8 of Fig. 7.

In the exemplification of the improvement disclosed by the drawings I make use of two jaw members which are in the nature of plates, each being of an equal width, length and thickness, and each of the plates having one of its ends bent, the said bent ends being extended toward each other and being formed with interengaging knuckles through which a pintle passes whereby to hingedly connect the jaws.

In the preferred embodiment of the improvement one of the jaws is indicated by the numeral 1 and the other by the numeral 2. The jaw 1 is provided on its inner face by a substantially rectangular shank 3. The shank has its corners beveled as at 4 and is provided, adjacent its outer edge, with an elongated slot 5. The shank is in the nature of a comparatively thin plate, the thickness of which being slightly less than the bore or socket 7 provided on the inner face of the jaw 2. The socket 7 is provided by forming the inner face of the jaw 2 with an upturning substantially rectangular flange 8.

In the socket 7, and preferably seated in a longitudinal groove 9 therein, is a spring. The spring is in the nature of a U-shaped member, and is broadly indicated by the numeral 10. The longitudinal arms of the spring, at approximately the central portion thereof, are bent inwardly providing what may be termed lips and which are indicated by the numerals 11.

95 Entering the socket, from the outer end of the jaw 2 is a plunger 12. This plunger has on its inner end a substantially V-shaped head 13, and the said head is in the path of engagement with the offset free ends 14 of the spring 10. It will be apparent that by an inward pressure upon the plunger 12 the arms of the spring 10 will be forced away from each other, so that the lipped portions 11 thereof will be brought out of the notch 5 of the shank 3, when the jaw 1 is swung over the jaw 2. It will also be apparent that by swinging the jaw 1 over the jaw 2 the shank 3 will freely enter the socket and will be properly engaged by the lips 11 of the spring. The depth of the socket limits the movement of the shank 3.

therein and also arranges the notch 5 in proper position to be engaged by the inturning portions 11 of the spring 10. The plunger 12 does not project beyond the end of the jaw 2, but the said jaw 2 is formed with a depression 15 that surrounds the outer end of the plunger. This permits of the finger nail of the operator being brought into proper contact with the plunger to move the same longitudinally, and the plunger is returned to its normal position by engagement of the offset free ends 14 of the spring 10 therewith.

In the construction illustrated in Figs. 6 to 9 inclusive, one of the jaws 16 has a shank 17 that is provided with an arrow head 18. The second jaw 19 has on its inner face an upstanding substantially rectangular member 20, the bore of which provides the socket for the shank 17.

Pivotedly secured, as at 21, to the end members of the socket 20 are two plates 22 respectively. The plates have their upper ends hooked as at 23 and their lower ends provided with inturned flanges 24. Each of the hooked members of the plates 22 is influenced by a spring 25, the latter forcing the said plates toward each other, and the hooks are limited in such direction by the contacting engagement of the flanges 24 thereof. It will be apparent that when the jaw 16 is swung over the jaw 19 to bring the shank 17 in the socket 20 the hooks 23 of the plates 22 are right over the arrow head 18 and engage with the upper shoulders 26 provided thereby.

To release the hooks a plunger 27 is employed. This plunger passes through a suitable opening in the jaw 19 centrally of

the socket 20 and has its upper end provided with a head 28. It will be apparent that by a pressure of the plunger to bring the same in the housing 20 will cause the head 28 of the said plunger to contact with the flanges 24 of the hook plates 22 to swing the latter on their pivots 21 against the pressure of their springs 25, and thus release the shank 17 of the jaw 16, permitting the latter to be swung away from the jaw 19.

Figure 1 illustrates the manner in which the button is applied to the cuff of the shirt, and it is thought that the foregoing description, when taken in connection with the drawings will fully set forth the simplicity and advantages of the construction. In this connection it is to be understood that the description and the showing of the drawings are indicated merely to set forth the satisfactory embodiments of the invention as it now appears to me, but I am entitled to make all such changes therefrom as fall within the scope of my claim.

Having described my invention, what I claim is:

A cuff button comprising two plates having offset ends which are hingedly connected together, a shank on one of the plates, the other plate having a socket to receive the shank, spring influenced means disposed in the socket adjacent to the sides thereof, interengaging means between said spring means and the shank when the latter is received in the socket, whereby to lock the shank in the socket, and means arranged for movement between the locking means for spreading the latter and releasing the shank.

In testimony whereof I affix my signature.
CHARLES L. FAULK.
